UNITED STATES PATENT OFFICE

132,739

DESIGN FOR A FOLDING CIGARETTE CASE

Royal R. Miller, Los Angeles, Calif.

Application March 26, 1941, Serial No. 99,903

Term of patent 7 years

To all whom it may concern:

Be it known that I, Royal R. Miller, a citizen of the United States and a resident of Los Angeles, county of Los Angeles, State of California, have invented a new, original, and ornamental Design for a Folding Cigarette Case, of which the following is a specification, reference being had to the accompanying drawing, forming a part thereof.

Referring to the drawing:

I claim:

The ornamental design for a folding cigarette case, as shown.

ROYAL R. MILLER.
